UNITED STATES PATENT OFFICE

LLOYD M. SHOUP, OF GOSHEN, INDIANA

INTERNAL-COMBUSTION ENGINE

Application filed June 27, 1929. Serial No. 374,039.

This invention relates to internal combustion engines of the four cycle type, and especially to valve mechanism therefor.

The principal object of the invention is to provide a four-cycle gas engine with a single piston valve for controlling the fuel supply and exhaust in an efficient and noiseless manner.

Another object of the invention is to provide a single reciprocating piston valve for a four-cycle gas engine, wherein both the fuel inlet and exhaust ports are formed in the valve, which ports are suitably timed to alternately register with fuel inlet and exhaust ports formed in the engine cylinder wall.

Still another object of my invention is to provide a piston valve of the character described which has a very limited reciprocating movement and which is provided with a fuel chamber, inlet and outlet fuel ports for said chamber, and a longitudinal exhaust passage in said valve, whereby the fuel gas is preheated prior to its inspiration to the engine working cylinder.

Other and more specific objects of the invention are mentioned and described herein.

The preferred embodiment of my invention is illustrated in the accompanying drawing, wherein

Figure 1 is a vertical transverse sectional view of a single cylinder engine of the four cycle type having my invention applied thereto and illustrating the relation between the power piston and valve in two positions of the piston;

Figure 2 illustrates a similar view in fragment showing the piston descending on the working stroke and the relative position of the valve;

Figure 3 is a similar fragmental view showing the piston at the bottom of the working stroke, the open exhaust ports, and the piston about to begin the scavenging stroke; and

Figure 4 is a similar fragmental view showing the piston again descending on the fuel inspiration, or suction, stroke with the inlet passages and ports in registration to admit the fuel.

Similar numerals of reference indicate like

parts throughout the several views on the drawing.

Referring to the details of the drawing the numeral 1 indicates an engine cylinder of the four-cycle type in which the piston 2 is reciprocally arranged and operatively connected with the usual crank 3 mounted on the usual crank-shaft 4, by the conventional connecting rod 5. A cylinder head 6 may be provided to close the upper end of the cylinder 1 and also the upper open end of the valve cylinder 8, the latter being arranged sidewise of the cylinder 1. A spark plug of any suitable type may be mounted at 7 in the head 6 to ignite the fuel charge, as is well known in the art.

The wall of the cylinder 1 adjacent the valve cylinder 8 is provided with the fuel inlet port 9 and an exhaust port 10, the latter being arranged above the former, and both ports in communication with the interior of the valve cylinder 8 adjacent the top end of both cylinders, and both ports under the control of the cylindrical piston valve 11 which is reciprocally arranged in cylinder 8, as hereinafter described.

The valve 11 is adapted to be reciprocally actuated by suitable half-timing mechanism and which may include the half-time driving gear 12 mounted upon and driven by the crank-shaft 4, said gear meshing with the larger driven gear 13 which is mounted upon a shaft 14 suitably journaled in the engine frame, said shaft extending transversely of the axis of the valve cylinder 8. The shaft 14 carries an eccentric 15 rigid therewith and with which the lower end of the valve actuating connecting rod 16 is operatively connected, the upper end of said connecting rod being pivotally and operatively connected at 17 with the lower end of the valve 11. This valve actuating mechanism imparts a rather limited half-timed reciprocating movement to the valve 11 but sufficient to alternately open and close the fuel inlet and exhaust ports, as hereinafter described. For supplying the engine cylinder with fresh gas the valve 11 is provided with the interior fuel chamber 18 and the latter is provided with a fuel outlet port 19 adjacent the top thereof and adapt-

ed to register with the cylinder fuel inlet port 9, said valve chamber being provided also with a fuel inlet port 20 adjacent the valve bottom, said port 20 being adapted to 5 register with the inlet supply port 21 formed in the wall of the valve cylinder and which may be connected with the engine carburetor—not shown—or any suitable source of fuel supply.

10 The numeral 22 indicates an exhaust passage extending longitudinally, preferably axially, of the valve 11 and open at the top end of said valve to receive the exhaust gases from cylinder port 10 at the proper time, the 15 lower end of said exhaust passage terminating above the bottom of the valve 11 in a bend or lateral outlet 23 which is adapted to register with the exhaust port 24 formed in the valve cylinder wall, the valve fuel inlet port 20 being positioned below the exhaust 20 passage port 23.

As illustrated in Fig. 1 the piston 2—solid lines—is about to begin its fuel compression stroke, showing ports 9 and 10 closed by the 25 side wall of the valve 11, in which position of the parts the valve port 19 is disposed slightly above the fuel inlet port 9 and so remains until the piston has passed the port 9 in its upward movement on the compression 30 stroke and during which piston movement the valve 11 has slight reciprocatory movement on account of the position of the eccentric 15 which has moved from the solid line to the dotted line position indicated in Fig. 1. 35 In this same Figure 1 the dotted lines of the piston 2 indicate the top of its stroke and as said piston rides upwardly over port 9 the valve port 19 begins to descend to gain a position below cylinder port 9 where it remains 40 during the working stroke of the power piston 2.

Continued downward movement of the piston 2 on its working stroke causes the upper end of the valve 11 to uncover port 10, thereby 45 releasing the exhaust gases through valve passage 22 and ports 23 and 24, said ports and passages remaining in registration, to an extent, during the upward scavenging stroke of the piston, upward movement of the valve 50 11 being retarded by the position of the eccentric 15 which has about reached its lowermost limit, Fig. 3.

As the valve 11 travels upward again port 55 10 is closed by the valve upper end, on the piston scavenging stroke, as the piston reaches its approximate upward limit, the valve 11 continuing its upward movement until ports 9 and 19 are placed in registration, port 19 60 ultimately finishing its movement at a point above port 9, Fig. 1.

From the foregoing it will be evident that 65 the fresh fuel gases enter valve chamber 18 through the port 21 and are preheated by contact with the hot walls of the exhaust

passage 22 prior to their entry to the working cylinder through port 9.

I claim:

1. In an internal combustion engine, a power cylinder, a valve cylinder adjacent thereto, 70 a fuel inlet port for the power cylinder, an exhaust port therefor positioned above said fuel inlet port, said exhaust port establishing communication between said power and valve cylinders adjacent the top end of the latter, and a reciprocatory piston valve in said valve cylinder, said valve being a hollow cylindrical element provided with an interior longitudinal exhaust passage open at the valve top end and adapted to receive the exhaust gases from 75 said power cylinder exhaust port, said valve exhaust passage having an exhaust outlet at its lower end, said piston valve being provided also with an interior fuel chamber having fuel inlet and outlet ports, the latter being adapted to register with said power cylinder inlet port.

2. In an internal combustion engine, a power cylinder, a valve cylinder adjacent thereto, a fuel inlet port for the power cylinder, an exhaust port therefor positioned above 80 said fuel inlet port, said exhaust port establishing communication between said power and valve cylinders adjacent the top end of both said cylinders, adjacent fuel inlet and exhaust ports provided in the outer wall of said valve cylinder, the latter being above the former, and a reciprocatory piston in said valve cylinder, said valve being a hollow cylindrical element provided with an interior longitudinal exhaust passage permanently 85 open at the valve top end and in permanent communication with the valve cylinder to receive the exhaust gases from said power cylinder exhaust port, said valve exhaust passage having an outlet adjacent its lower end adapted to be placed in communication with the exhaust port in said valve cylinder wall, said piston valve being provided also with an interior fuel chamber having fuel inlet and outlet ports which are adapted to register, respectively, with said valve cylinder fuel inlet port and the power cylinder fuel inlet port.

3. In an internal combustion engine, a power cylinder, a valve cylinder adjacent thereto, a fuel inlet port for the power cylinder, an exhaust port therefor positioned above said fuel inlet port, said exhaust port establishing communication between said power and valve cylinders adjacent the top end of both, a reciprocatory piston valve in said valve cylinder, said valve being a hollow cylindrical element provided with an interior longitudinal exhaust passage which is open at its top end to receive the exhaust gases from the upper end of the valve cylinder after the latter has received said gases from the power cylinder through said power cylinder exhaust port, said valve exhaust pas- 120 125 130

1 sage having an exhaust outlet adjacent its lower end, said piston valve being provided also with an interior fuel chamber having fuel inlet and outlet ports, the latter being adapted to register with said power cylinder fuel inlet port, and means for reciprocally actuating said piston valve, said means comprising half timing gears actuated by the engine crank-shaft, a valve actuating shaft 5 which rotates at one half the speed of the engine crank-shaft, an eccentric on said shaft, and an eccentric rod operatively connecting said eccentric and piston valve.
